(57) **CLAIM**

The ornamental design for a wiper for automobile, as shown and described.

DESCRIPTION

FIG. 1 is a perspective view of the wiper for automobile.

FIG. 2 is a front view of the wiper for automobile.

FIG. 3 is a rear view of the wiper for automobile.

FIG. 4 is a first side view of the wiper for automobile.

FIG. 5 is a second side view of the wiper for automobile.

FIG. 6 is a plan view of the wiper for automobile.

FIG. 7 is a bottom view of the wiper for automobile.

FIG. 8 is an enlarged sectional view of the wiper for automobile taken along a line 8-8 in FIG. 4.

FIG. 9 is an enlarged front view of an end of the wiper for automobile indicated by region 9 in FIG. 2.

FIG. 10 is an enlarged plan view of the end of the wiper for automobile indicated by region 10 in FIG. 6.

FIG. 11 is an enlarged bottom view of the end of the wiper for automobile indicated by region 11 in FIG. 7.

FIG. 12 is an enlarged first side view of the wiper for automobile; and,

FIG. 13 is an enlarged second side view of the wiper for automobile.

In the drawings, the broken lines depict portions of the article that form no part of the claimed design.
